UNITED STATES PATENT OFFICE

162,055

PRESSURE REGULATOR

John L. Matasovic, Chicago, Ill.

Application March 9, 1949, Serial No. 1,307

Term of patent 14 years

(Cl. D78—1)

To all whom it may concern:

Be it known that I, John L. Matasovic, a citizen of the United States, residing at Chicago, in the county of Cook and State of Illinois, have invented a new, original, and ornamental Design for a Pressure Regulator, of which the following is a specification, reference being had to the accompanying drawings, forming a part thereof.

In the drawings:

Figure 1 is a front perspective view of a pressure regulator showing my new design, and

Figure 2 is a rear perspective view thereof.

I claim:

The ornamental design for a pressure regulator, substantially as shown.

JOHN L. MATASOVIC.
